[57] CLAIM

The ornamental design for a lighter, as shown and described.

DESCRIPTION

FIG. 1 is a front perspective view from above of the lighter showing my new design,
FIG. 2 is a front elevation thereof,
FIG. 3 is a side elevation thereof,
FIG. 4 is a rear elevation thereof,
FIG. 5 is the other side elevation thereof, and
FIG. 6 is an underneath view thereof.
The characteristic feature of the lighter is the tunnel-shaped lid.
